UNITED STATES PATENT OFFICE.

GEORGE SHEPARD JOHNSON, OF MADISON, WISCONSIN, ASSIGNOR TO C. F. BURGESS LABORATORIES, INC., OF MADISON, WISCONSIN, A CORPORATION OF DELAWARE.

MEANS FOR REMOVING CONDENSATE FROM STEAM-HEATED ROLLERS.

Application filed July 21, 1926. Serial No. 123,911.

This invention relates to improvements in means for removing condensate from steam heated rollers. Such rollers or rolls are used in various arts, for example, in the paper industry in which the web is dried as it travels in contact with a series of rolls of fairly large diameter. The rolls are steam tight, the steam being admitted through the hollow journals. In starting the operation, when the rolls are cold, the steam condenses rapidly, resulting in the immediate accumulation of a considerable amount of water in the roll, which condensate may be augmented during the continued operation of the rolls, depending on the pressure and temperature maintained within the same. It is necessary to withdraw this condensate through the hollow journal, an operation which in some cases could not be performed when the rolls were stationary and in other cases, was unsatisfactory for other reasons, including slow and uneven heating.

The general object of this invention is to provide improved means for removing said condensate through the journal in such a way that the roll heats up quickly and maintains a more even temperature.

Other objects are to provide a device of this character which will drain the roll of water whether said roll is stationary or rotating; which will prevent steam from blowing out after most of the water has been drained therefrom; and which if suction is used to withdraw said water will not operate so as to cause the suction to break.

An additional object is to provide means whereby said device may be readily reached for inspection, renewal and repair.

In the drawings, in which one embodiment of the invention has been illustrated,

Figure 1 is a sectional elevation of a roll and its appurtenances.

Fig. 2 is an end elevation thereof on a smaller scale.

Fig. 3 is an enlarged sectional elevation of a trap, including a needle-valve operated by a float.

Fig. 4 is a horizontal section through the hollow journal of said roll.

The roll illustrated in the drawings is one such as is used in the paper industry, although the invention is not limited to this art. Said roll comprises a cylindrical metal shell 10 having end plates or heads 11 secured thereto, the structure thus formed being rotatably

supported by journals, 12, 13, which turn in suitable bearings, not shown. Steam for heating the roll is supplied through a stationary structure which is held against an extension 14 on the end of the hollow journal 13 in the usual manner, forming no part of the present invention. Said stationary structure comprises a hollow member to which steam is admitted through a passageway 15 connected with a suitable supply pipe, not shown, whereby steam is introduced into the interior of the cylinder through said hollow journal.

Water of condensation is removed through a passageway 16, formed in the same member 17 which contains the steam passageway 15, said member forming a closure for the adjacent seam inlet chamber. A pipe 18 is arranged preferably coincident with the axis of rotation of said cylinder, extending from the inner wall of the passageway 16 into the cylinder and then curving downwardly and terminating near the lowest part of the cylinder and preferably near the opposite end of said cylinder. Said pipe may be supported further by a skeleton frame or spider 19 mounted thereon and resting on the cylindrical inner wall of the hollow journal 13. The end of said shaft may be provided with a coupling 20 which receives a screw threaded plug 21 constituting an adjustable valve seat and having an opening 22 which receives a needle valve 23, the latter being pivoted at one end to a projection 24 on an arm 25. Said arm is pivoted at 26 to a bracket 27 carried by the coupling 20. The free end of said arm 25 carries a float 28 consisting of a hollow structure of any suitable configuration.

The arrangement is such that the weight of the parts maintains the needle valve closed when said parts are in normal position, as shown in Fig. 3. When said float 28 is raised by being submerged in the water condensing in the cylindrical roll 10, said needle valve is withdrawn from its seat, somewhat as shown in dotted line position in said figure. The parts are so proportioned that the float is not raised until after the water level is above said needle valve, thus preventing waste of steam which would otherwise blow out through said pipe 18. When the valve is submerged and opened, the pressure of the steam on the surface of the water will force the latter through said valve and through the outlet pipe 16, reducing the level to approximately that of the needle valve, or preferably

slightly above it, by which time the float has descended sufficiently to close said valve. Under these circumstances, it will be seen that water remaining in said roller is comparatively shallow in depth, and therefore is not very effective as a non-conductor of heat between the hot interior of the roll and the web in contact with the outer surface.

The device operates effectively whether the 10 rolls are stationary or rotating. When the rolls are rotating, as suggested by the arrow in Fig. 2, the surface of the water is not horizontal, but assumes somewhat of an incline (see dotted line), depending on the speed of 15 rotation, since the water adheres to the inner surface of the roller. Therefore, the trap, consisting of the needle valve and associated parts heretofore described, may be offset a little with reference to the vertical plane passing 20 through the axis of rotation of said roll, if desired, although normally it would be located at the lowest point within said cylindrical chamber and preferably remote from the steam inlet in a region where the initial 25 condensation is most rapid.

By maintaining the level of the condensate at as low a point as possible at the outset, the

roll heats up quickly and the heat is evenly distributed when the rolls is in operation.

If suction is applied to the outlet pipe, 30 said suction is never broken as the valve is open only when it is submerged.

The steam trap may be readily installed or removed for inspection or adjustment through the hand-hole 29 after removing the 35 cover-plate 30.

I claim as my invention:

A device of the class described, adapted to be mounted in close proximity to the bottom of a container, comprising a pipe having a 40 collar threaded on the open end thereof, an adjustable plug fitting said collar and having a small opening therethrough, a bracket secured to said collar, an arm hinged to said bracket, a downwardly extending projection 45 on said arm, a needle valve carried by said projection and received within said opening for closing the same and a float secured to the free end of said arm adapted to move said arm upwardly for moving the needle valve to open 50 position.

In testimony whereof, I have subscribed my name.

GEORGE SHEPARD JOHNSON.
